UNITED STATES PATENT OFFICE.

WILBUR A. RICE, OF ALTOONA, PENNSYLVANIA.

MAUSOLEUM AND MEANS FOR VENTILATING IT.

1,183,668.

Specification of Letters Patent.

Patented May 16, 1916.

Application filed May 19, 1915. Serial No. 29,076.

To all whom it may concern:

Be it known that I, WILBUR A. RICE, a citizen of the United States, residing at Altoona, in the county of Blair and State of Pennsylvania, have invented certain new and useful Improvements in Mausoleums and Means for Ventilating Them.

One of the most desirable features of a mausoleum is to have it dry and sanitary, and with this object in view I have invented a system of ventilation and sanitation, of which the following is a specification, and the combination and arrangement of parts is shown in the accompanying drawings, in which—

Figure 1 is a horizontal section through the crypts. Fig. 2 is a vertical section on line C—D Fig. 1. Fig. 3 is a vertical section on line A—B of Fig. 2. Fig. 4 is a perspective view of the vertical section through one of the walls between the crypts on line E—F Fig. 1.

My invention is more particularly described as follows:—A suitable foundation 25 of concrete or other material such as is shown at "1" and "2", is first built. Upon this is placed a sanitary floor "3" built of concrete or other suitable material. Vertical walls "4" are supported upon the floor 30 "3" and built at suitable distances apart for making the size of crypt required. These are also preferably of concrete. Floors "5" are provided at suitable distances apart to make the space for the crypts required horizontally. The first floor is placed a distance 35 above the floor "3" of the mausoleum so as to leave a ventilating space "7" between the first floor of the crypt and the floor of the mausoleum. Above the crypts is the roof. 40 This is also spaced so as to leave room for ventilation, as shown at "9". In the rear of the crypts between the outside wall of the mausoleum "21" and the crypts themselves is a space "8" which communicates 45 with the space "7" and the space "9". The front of these crypts is preferably lined with marble or other ornamental materials, and at intervals in the lower slab near the floor are placed ventilating openings or screens, 50 such as shown at "10", and in the slab between the upper crypt and the roof are placed similar ventilating openings "11". In the space between the opening "11" and the main roof of the mausoleum is an opening "12", preferably provided with louvers, 55 as shown in Fig. 4. By reference to this

figure it will be seen that above the crypts and directly over the main corridor is a clear story with these openings "12" in the sides at intervals along the same. Any other 60 method of accomplishing the same object, which is to communicate directly from the main corridor to the outer air above the crypts, may be employed and is within the scope of applicant's invention. I have also 65 provided openings "10" through the outer walls and communicating with the air chambers, which will aid circulation.

The ventilation for the crypts is provided by means of a system of manifolds and pipes 70 leading therefrom to the various crypts, all of which are embedded in the concrete walls of said crypts, as are shown and explained in the applicant's patent No. 1,123,379, dated January 5th, 1915, and a similar system of 75 manifolds and pipes is placed at the bottom and connected to a seepage tank "14" with pipes running upward to the various crypts in order to take care of any seepage or drainage that may be necessary from the same. 80 The upper manifolds shown at "16" are connected to a sanitary disinfecting trap "17", which communicates with the pipe "18" and opening "19" that pass through the roof and curve downward to prevent the elements 85 from affecting the interior. The cap "20" is used for introducing the disinfectant into trap "17", as is fully explained in applicant's patent above referred to. These 90 crypts and walls are preferably made of concrete and are reinforced in the ordinary manner so as to make them seamless, so that each crypt is independent of every other one and the system of drainage and ventilation takes care of each individual crypt as 95 above described. Any other suitable material could be substituted for concrete, and applicant does not wish to limit his construction to that material. It is well known, however, that most substances are porous to 100 a greater or less extent and, therefore, gases are liable to escape through the walls. If no special provisions are made to take care of these gases they would be obnoxious in 105 the mausoleum, which is used by the public, and might become dangerous. With a view of eliminating this danger, applicant has made his construction as above described so that the entire system of crypts is ventilated on the outside and entirely independent of 110 the interior ventilation and sanitation of the crypts. By reason of this construction,

which forms a building within a building leaving a ventilating space between, all condensation due to atmospheric conditions is also eliminated, thereby making the entire 5 building dry and sanitary.

By reference to Fig. 4 of the drawings, it can readily be seen that air, which naturally rises, would enter the openings "10", pass under the crypts, rise through the space "8", 10 thence through the space "9" between the roof and the crypts and leave at "11". This air would then pass out of the mausoleum through the openings "12", thereby keeping the interior free from obnoxious gases or 15 fumes which otherwise might contaminate the air.

I do not intend to limit myself to the specific form of ventilating shown, but any system that will accomplish the same object 20 may be employed.

Therefore what I claim is—

1. In a mausoleum comprising a floor, a corridor and a series of crypts on each side thereof, ventilating spaces between said 25 crypts and floor and outer walls and roof of the mausoleum, openings from said corridor

to said spaces under the crypts and also above the crypts, openings through the exterior walls of the mausoleum into said ventilating spaces near the bottom; said exterior walls being imperforate at the upper portion of the crypts, and outlet openings 30 at the roof of the mausoleum.

2. A mausoleum comprising outer walls and a corridor with a series of crypts on 35 each side thereof, said crypts being entirely surrounded with air spaces within the exterior walls of the mausoleum, the space beneath the crypts having openings adjacent the floor communicating with the corridor, the space above the crypts having openings 40 communicating with the corridor, outlet openings near the roof of the structure, openings through the exterior walls of the mausoleum into said ventilating spaces near 45 the bottom, and said exterior walls being imperforate at the upper portion of the crypts.
